HARRY F. ROACH,

by Bakewell & Company, ATTORNEYS.

UNITED STATES PATENT OFFICE.

HARRY F. ROACH, OF ST. LOUIS, MISSOURI.

RAIL-JOINT.

1,361,775.

Specification of Letters Patent. Patented Dec. 7, 1920.

Application filed March 16, 1920. Serial No. 366,206.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to rail joints of the type known commercially as "Roach" joints or "Roach" bars, wherein the joint members are provided intermediate their ends with rail engaging portions so constructed and arranged that the terminals of the rails fulcrum on the joint members under load, thereby permitting the wave motion of the rails throughout the track to be continued uniformly through the joints 20 of the track.

One object of my present invention is to provide a rail joint of the type above referred to in which the joint members are of such design that the fulcrum points of 25 the rails on said members can be maintained at a predetermined point or within a predetermined zone, regardless of the wear on the portions of the joint members that bear against the heads and the base flanges of the 30 rails.

Another object is to provide a rail joint member or bar of the kind just referred to, which is equipped with means that tends to prevent the material in the rail engaging 35 portions of the member from flowing when the joint member is in service.

And still another object is to provide an inexpensive and efficient one-piece rail joint member or bar of the "Roach" type that 40 can be forged easily or formed from a rolled member by shearing off portions of said member and punching bolt holes in the same either in one operation or in successive operations.

45 Figure 1 of the drawings is a side elevational view of a rail joint constructed in accordance with my invention.

Fig. 2 is a view, showing one of the joint members in end elevation and the other joint 50 member in vertical cross section; and

Fig. 3 is a top plan view of a portion of one of the joint members.

Referring to the drawings which illustrate the preferred form of my invention, 55 A designates two members or bars that are arranged on opposite sides of two abutting

rails B, and C designates bolts that pass transversely through the webs of the rails and through the joint members A so as to hold said joint members in operative engagement with the rails. Each of the members A is provided intermediate its ends with two rail engaging portions 1 that bear against the undersides of the heads of the rails and against the upper sides of the base flanges of the rails, the rail engaging portions 1 extending a short distance on each side of the space between the ends of the rails, as shown in Fig. 1. The end portions of each of the joint members A are spaced away from the heads and base flanges of the rails so as to permit the rails to deflect slightly and also move upwardly at the ends of the joint, under load, as is usual in "Roach" rail joints.

The novelty of my present invention consists in forming the rail engaging portions 1 of each joint member in such a manner—

(1) That the fulcrum points of the rails on the joint members can be maintained at 80 a predetermined point or within a predetermined zone;

(2) That the tendency of the material in the rail engaging portions 1 of the joint member to flow, is reduced to a minimum; 85 and

(3) That the member A can be forged easily or formed from a rolled member by shearing off portions of the rolled member and punching bolt holes in the same in one 90 operation or in successive operations.

As shown in the drawings, the member A consists of a bar, preferably of the cross section shown in Fig. 2, whose end portions are of less depth or height than the intermediate portion of the bar, which comprises the rail engaging portions 1 that bear against the heads and the base flanges of the rails. The upper and lower edges of the end portions of the member A, namely, the portions lying between the rail engaging portions 1 and the ends of the member, may be parallel and spaced away from the heads and base flanges of the rails, or they may be slightly inclined, as shown in Fig. 1. Said upper and lower edges are so formed, however, that they do not form continuations of the surfaces at the upper and lower edges of the deep intermediate portion of the member A that bear against the undersides of the heads and against the upper sides of the base flanges of the rails. In other words, the member A

is so formed that the upper and lower edges of the end portions of the same do not merge into the surfaces on the deep intermediate portion of the member that bear against the rails. The object of constructing the member A in this manner is to eliminate the possibility of the length of the rail engaging surfaces on the portions 1 increasing, as said surfaces wear away, and thus causing the fulcrum points of the rails on the member A to move outwardly away from the center of the joint. For example, if the member A were provided at its center with rail engaging portions having surfaces that merged into the upper and lower edges of the end portions of the member A, the length of the rail engaging surfaces of the member that contacted with the heads and base flanges of the rails would increase as said surfaces wore away, due, of course, to the fact that the upper and lower edges of the end portions of the member formed continuations of said rail engaging surfaces, thus resulting in the fulcrum points of the rails on the joint members moving outwardly toward the ends of the joint.

In a rail joint of the "Roach" type it is highly desirable to maintain the fulcrum points of the rails within certain predetermined limits, regardless of the wear on the rail engaging portions of the joint members. This is possible with a joint member or bar of the construction herein shown on account of the fact that the intermediate portion of the bar that contains the rail engaging portions 1 is so proportioned with relation to the end portions of the bar that the rail engaging surfaces of the portions 1 do not merge into the upper and lower edges of the end portions of the bar. Stated in another way, the joint member A herein illustrated is provided with rail engaging portions 1 whose rail contacting surfaces are located high enough above the upper edges of the end portion of the member and far enough below the lower edges of the end portion of the member to eliminate the possibility of said rail contacting surfaces increasing in length, due to said surfaces wearing way and gradually merging into the upper and lower edges of the end portions of the member A.

In practice I prefer to form fillets 1^a at the ends of the rail engaging portions 1, so as to tend to prevent the material in said rail engaging portions 1 from flowing toward the ends of the joint or mashing down, due to the pressure which is imposed on the rail engaging portions 1 when the member A is in service. These fillets 1^a not only tend to eliminate mashing down of the ends of the rail engaging portions 1, but they reinforce and strengthen the member A at the points where the relatively shallow end portions of the member branch laterally from the deep

intermediate portion of the member, due, of course, to the fact that they cause the section of the member A to change gradually instead of abruptly at the vital point of the member A.

A rail joint member or bar of the construction above described can be forged easily or it can be manufactured at a low cost by taking a rolled member of substantially the cross section represented by the intermediate portion of the member A, and then shearing off sufficient material from the end portions of said rolled member to form a member A of the shape herein illustrated, the bolt holes in said member being punched simultaneously with the shearing operation or by a separate and distinct operation.

A rail joint member of the construction above described has all of the desirable characteristics of the "Roach" rail joint or bar now in commercial use in addition to the features previously pointed out.

Having thus described my invention, what I claim as new and desire to secure by Letters Patent, is:

1. A rail joint member or bar having its end portions spaced away from the heads and base flanges of the rails so as to permit the rails to fulcrum on said member and provided intermediate its ends with rail engaging portions so designed that the length of the same will not increase when the rail contacting surfaces on said portions wear away.

2. A rail joint member or bar having its end portions spaced away from the heads and base flanges of the rails so as to permit the rails to fulcrum on said member and provided intermediate its ends with integral rail engaging portions whose rail contacting surfaces do not merge into the upper and lower edges of the end portions of said member.

3. A rail joint member or bar having its end portions spaced away from the heads and base flanges of the rails so as to permit the rails to fulcrum on said member and provided intermediate its ends with integral rail engaging portions that are adapted to bear against the heads and the base flanges of the rails, and means that tends to prevent the material in said rail engaging portions from flowing when the member is in service.

4. A rail joint member or bar having its end portions spaced away from the heads and base flanges of the rails so as to permit the rails to fulcrum on said member, and a relatively deep intermediate portion on said member provided with surfaces that bear against the undersides of the heads and against the upper sides of the base flanges of the rails, the upper and lower edges of the end portions of said member being so disposed with relation to the rail contacting surfaces of said intermediate portion

that the length of said rail contacting surfaces will not increase as said surfaces wear away.

5. A rail joint member or bar formed in one piece and provided intermediate its ends with a relatively deep portion having surfaces thereon that bear against the undersides of the heads and against the upper sides of the base flanges of the rails, the 10 top and bottom edges of the end portions of said member being so designed that no portions of the same contact with the heads and base flanges of the rails during the life of the member.
15. 6. A rail joint member or bar having its end portions spaced away from the heads and base flanges of the rails so as to permit the rails to fulcrum on said member and provided intermediate its ends with rail engag- 20 gaging portions that project above and be-

low the upper and lower edges, respectively of the end portions of said member, and fillets located at the ends of said rail engaging portions.

7. A rail joint member or bar consisting 25 of a rolled member having an intermediate portion of such cross section that the upper and lower edges of the same will bear against the undersides of the heads and the upper sides of the base flanges of the rails, 30 the upper and lower edge portions of the parts of said member which lie on opposite sides of said intermediate portion being sheared off so as to provide sufficient clearance between the edges of the end portions 35 of said member and the heads and base flanges of the rails to permit the rails to rock vertically under load.

HARRY F. ROACH.
